UNITED STATES PATENT OFFICE

2,194,653

FLOOR MAT

George F. Gell, East Cleveland, Ohio, assignor, by direct and mesne assignments, to The Maier Products Company, Inc., Cleveland Heights, Ohio

Application October 1, 1938, Serial No. 232,818

6 Claims.

(Cl. 20—78)

This invention relates to floor mats, and more particularly to rubber mats.

It is one of the objects of the invention to provide a mat that may be made up of blocks of rubber in any desired color or combination of colors, or containing any desired design or lettering, whereby mats may be conveniently and easily constructed to embody any desired ornamental design or lettering for advertising or other purposes.

A further object of the invention is to provide a mat construction that may be made in any desired width or length, and that will embody perforations whereby water accumulating on the surface of the mat will pass through to the floor.

A further object of the invention is to provide a construction in which the body of the mat is supported off the floor so that the space below the mat will be ventilated and any water will be permitted to escape.

Other objects of the invention and the features of novelty will be apparent from the following description taken in connection with the accompanying drawing, in which:

Fig. 1 is a plan view of a fragment of a mat embodying my invention, some of the composition blocks forming the upper surface of the mat being omitted to show the construction of the metal base.

Fig. 2 is a section on the line 2—2 of Fig. 1.

Fig. 3 is an edge view of one end of the mat.

Fig. 4 is a plan view of one of the blocks comprised in the construction illustrated in Fig. 1.

Fig. 5 is an edge view thereof or side elevation.

Fig. 6 is a detached plan of a fragment of the nosing strip shown in Fig. 1.

Fig. 7 is an edge view or end elevation thereof.

Fig. 8 is a plan view of a special form of block which may be used in connection with the block illustrated in Figs. 4 and 5 for the purpose of securing the design and arrangement illustrated in Fig. 1.

Fig. 9 is an edge view or end elevation of the block illustrated in Fig. 8.

Fig. 10 is a fragmentary plan of a mat having a base similar to that illustrated in Fig. 1, but with blocks of a modified form.

Fig. 11 is a plan view of one of the blocks illustrated in Fig. 10.

Fig. 12 is an edge view or side elevation thereof.

Referring to the drawing, 20 indicates a base of sheet metal or other suitable material having uniformly arranged perforations 21 therein, these perforations being preferably of X-shape and having an enlarged substantially square central portion 22 with four lobe-like extensions 23 therefrom. As will be evident from Fig. 1, the perforations 21 do not require four of the extensions 23 as, in the pattern illustrated, only two of the extensions, of each perforation, are employed.

However, I prefer to have four of the extensions 23 on each of the perforations so that when the blocks 24 have designs or lettering thereon they may be arranged on the base 20, as shown in Fig. 1, or turned 90° from the position shown so that the lugs 25 on the bottom of the blocks will engage with a different pair of extensions 23. This will permit the attachment of any of the blocks in four different arrangements and thus facilitate the making up of any desired pattern.

It will be noted that each of the lugs 25 has a head 26 thereon, the upper surface 27 of which is adapted to engage with the under side of the base 20. The reduced portion of the lug, between the block proper and the head 26 is adapted to fit in the lobe-like extension of the perforation 21, and it will be noted that between the rounded end portion of each of the extensions 23 and the central portion 22 of the perforation there is a narrowed portion 28 through which the lugs 25 may be inserted into the end portions of the extensions 23. The blocks 24 are preferably made of a resilient rubber composition and the lugs 25 will deform sufficiently to permit their insertion through the narrowed portion 28, above referred to.

In applying the blocks 24 one of the lugs thereof is first positioned in the desired extension 23 and then the block is stretched sufficiently to permit the other lug thereon to enter its cooperating extension 23 through the enlarged central portion 22 of the perforation. It should be further noted that the lugs of each block engage with extensions 23 of different perforations so that, when the blocks are in position on the base 20 they are interlocked, by means of the lugs 25, with the portion of the base lying between the extensions 23 that are engaged by the lugs.

The base 20 may be made of any desired width or length and the ends or, in fact, any of the edges of the base may be arranged in a nosing strip 29. This nosing strip is provided on its under surface with lugs 30 similar to the lugs 25 and adapted to engage with those perforations which lie beneath the nosing strip. The extreme edge portion of the base is preferably arranged in a slot 31 in the nosing strip which is, in effect, formed by a retroversion of the upper portion of the strip around underneath the base 20 as shown at 32. The upper surface of the strip 29, adjacent the end thereof, may be curved downwardly as indicated at 33 to form a tapering or sloping end which will reduce the thickness of the mat and thereby lessen the liability for the edge to act as a dangerous obstruction.

In order to permit water to flow from beneath the mat, the bottom surface of the nosing strip, which engages with the floor, is provided with a series of slots 34.

As will be seen from Fig. 1, the blocks 35 which

abut against the inner end of the nosing strip 29 are one-half the size of the blocks 24, so that a neat and harmonious design and arrangement is provided.

5 The blocks 35 are shown in detail in Figs. 8 and 9 and have two lugs 36 for engaging with perforations in the base 20.

The blocks 24, as will be noted from Figs. 1 and 4, are of octagonal shape with the edges of adjacent blocks in abutting relation and each group of four blocks together forming an opening 37 which registers with the enlarged central portion 22 of the perforations. These openings 37 allow water and dirt to pass from the upper surface of the mat to the floor below and also facilitate ventilation of the space beneath the mat.

Referring to the modification shown in Figs. 10, 11 and 12, it will be noted that the blocks 38 are substantially square or rectangular in shape with 20 V-shaped notches 39 on two opposite sides, these notches on abutting blocks forming a rectangular opening 40 which registers with the central portion 22 of the perforation beneath. Each of the blocks 38 has two lugs 41 on its under side for attachment to the base 20.

While I have illustrated and described two preferred forms of blocks it will be evident that blocks of other shapes may also be employed and that the perforations 21 may vary in form without departing from the spirit of the invention as defined in the appended claims. It will also be understood that the details of construction of the nosing strip 29 may be varied from the construction illustrated.

35 From the foregoing description it will be apparent that my improved mat construction may be made in any desired size or shape and that the metal base will provide a desirable degree of stiffness permitting several mats to be conveniently stored in piles and that by using blocks of various colors and with various designs thereon it is possible to produce an almost endless variety of designs of mats and that it is also possible to readily change the design or lettering on any particular mat by simply removing some of the blocks therefrom and replacing them with other blocks to form a different design or lettering. The metal base insures that the mat will retain its shape. In case the base becomes bent or dented by dropping a heavy weight on the mat or by running a heavily loaded truck over it, the metal may be readily restored to a flat condition by hammering out the bend or dent against a suitable flat surface.

55 Having thus described my invention, I claim:

1. In a floor mat, the combination of a sheet metal base having uniformly arranged perforations therein, and resilient composition blocks each having a plurality of lugs on one side which are interlockingly arranged in said perforations and project below said base to support the latter above the floor, and said blocks being so shaped that adjoining blocks will be in abutting relation and openings will be provided between the blocks which register with said perforations.

2. In a floor mat the combination of a sheet metal base having uniformly arranged perforations therein, and resilient composition blocks having a pair of lugs on one side, each of said lugs being provided with an enlarged head, one of the lugs on each block being arranged in one of said perforations and the other in another perforation, said perforations having enlargements

through which the heads on said lugs may be inserted and which are so spaced as to require stretching of said blocks in attaching them to said plate to provide an interlocking engagement of the lugs on each block with the portion on the 5 base that lies between the perforations that are engaged by the lugs of the block, said heads on the lugs being adapted to support said base above the floor, and said blocks being so shaped that adjoining blocks will be in abutting relation and 10 openings will be provided between the blocks in registration with said enlargements in said perforations.

3. In a floor mat, the combination of a sheet metal base having uniformly arranged X-shaped 15 perforations with enlarged central portions, and resilient composition blocks each having a pair of headed lugs on one side one of which engages with one of said perforations and the other of which engages another of said perforations, said lugs being engageable with said perforations through said enlarged central portions and the parts being so proportioned that when one of the lugs of a block is in position in a perforation the block must be stretched to enter the other 25 lug in the said enlargement of an adjacent perforation and when the block contracts to its normal size the lugs thereon will be in interlocking engagement with the portion of the base lying between these perforations.

4. In a floor mat the combination of a sheet metal base having uniformly arranged X-shaped perforations therein, and resilient composition blocks each having headed lugs on one side, the lugs of each block engaging adjacent perforations 35 whereby the block is interlocked with the portion of the base between these perforations, said blocks being so shaped that edges of adjoining blocks are in abutting relation and openings are provided between the blocks in registration with 40 the central portions of said perforations, the heads of said lugs engaging the under surface of said base and supporting the base off the floor.

5. In a floor mat, the combination of a sheet metal base having uniformly arranged perforations therein, resilient composition blocks having headed lugs on one side in interlocking engagement with said perforations, the heads of said lugs engaging the under side of said base and supporting the base off the floor, and a marginal strip for said base having headed lugs engaging some of said perforations and having an edge which is in abutting relation with edges of the blocks lying adjacent thereto, said strip being retroverted beneath the margin of said base and 55 acting as a support therefor.

6. In a floor mat, the combination of a sheet metal base having uniformly arranged perforations therein, resilient composition blocks having headed lugs on one side in interlocking engagement with said perforations, the heads of said lugs engaging the under side of said base and supporting the base off the floor, and a marginal strip for said base having headed lugs engaging some of said perforations and having an edge 65 which is in abutting relation with edges of the blocks lying adjacent thereto, said strip being retroverted beneath the margin of said base to support the latter and the bottom surface of the retroverted portion of said strip having passages 70 formed therein to permit the escape of water from beneath the mat.

GEORGE F. GELL.
